UNITED STATES PATENT OFFICE.

JOSEPH A. WOODMANSEE, OF NEW VIENNA, OHIO.

IMPROVEMENT IN CAR-COUPINGS.

Specification forming part of Letters Patent No. **202,622**, dated April 16, 1878; application filed July 27, 1876.

To all whom it may concern:

Be it known that I, JOSEPH A. WOODMANSEE, of New Vienna, Clinton county, Ohio, have invented an Improved Car-Coupling, of which the following is a specification:

Figures 1 and 2 are vertical longitudinal sections of a coupling embodying my invention in the opened and closed conditions, respectively. Fig. 3 is an end view. Fig. 4 is a top view.

A represents the draw-head, having the customary mouth or muzzle *a*, to receive the link, and vertical hole *a'*, for the coupling pin or bolt *B*. The coupling-bolt *B* has a **T**-head, *b*, which travels up and down in guides *C*.

A standard, *D*, which rises from the head *A*, affords journal-bearings *E* for trigger *F*, whose counter-arm *f* constitutes the lower member of a toggle, *fG*, whose upper member, *G*, is pivoted to the standard at *g*, and to a sliding catch, *H*, at *h*, which catch plays in a horizontal slot, *a''*, in the top of the head.

Accidental escape of the bolt *B* from the head is prevented by a block, *K*, whose removal enables the bolt to be unshipped when necessary.

A pin, *L*, inserted in a hole, *l*, in the guides, serves to hold the bolt *B* to its elevated

position independently of the trigger, when desired.

The operation is as follows: The draw-head is set to receive the link *I* of the opposing car by elevating the bolt *B* and engaging the catch *H* under the bolt-head, as in Fig. 1. This action advances the lower end of the trigger *F*, as seen in said figure. The link *I*, now approaching, pushes back the lower end of trigger *F*. This action straightens the toggle *fG*, and retracts the catch *H*, so as to liberate the bolt *B*, and to permit it to drop into and lock the link, as in Fig. 2.

The inner extremity of the locked link being held down by the shoulder or projection *J* of the interior of the head, the link is thereby held in a horizontal position, adapted to readily engage with the muzzle of an opposing car.

I claim as new and of my invention—

The coupling herein described, consisting of **T**-headed bolt *b*, standard *D*, guides *C*, catch *H*, toggle *fG*, and trigger *F*.

In testimony of which invention I hereunto set my hand.

JOSEPH A. WOODMANSEE.
